CLAIM

The ornamental design for a transition cup, as shown and described.

DESCRIPTION

FIG. 1 is a front perspective view of a transition cup showing our new design;

FIG. 2 is a rear perspective view thereof;

FIG. 3 is a front elevational view thereof;

FIG. 4 is a rear elevational view thereof;

FIG. 5 is a right side elevational view thereof, the left side elevational view being a mirror image thereof;

FIG. 6 is a top plan view thereof; and,

FIG. 7 is a bottom plan view thereof.

The broken lines in the drawings depict portions of the transition cup that form no part of the claimed design.

1 Claim, 7 Drawing Sheets
